CLAIM

The ornamental design for an infant walking trainer, as shown.

DESCRIPTION

FIG. 1 is a front elevational view of an infant walking trainer showing my new design;

FIG. 2 is a rear elevational view thereof;

FIG. 3 is a top plan view thereof;

FIG. 4 is a bottom plan view thereof; and

FIG. 5 is a right side elevational view thereof, the left side being substantially a mirror image of the right side shown herein.

FIG. 1

FIG. 5

FIG. 2

FIG. 3

FIG. 4
